UNITED STATES PATENT OFFICE.

RICHARD W. UHLIG, OF RUTHERFORD, NEW JERSEY, ASSIGNOR TO UNDERWOOD TYPEWRITER COMPANY, OF NEW YORK, N. Y., A CORPORATION OF NEW JERSEY.

TYPE-WRITING MACHINE.

1,117,279.

Specification of Letters Patent. Patented Nov. 17, 1914.

Application filed October 4, 1909. Serial No. 520,766.

To all whom it may concern:

Be it known that I, RICHARD W. UHLIG, a citizen of the United States, residing in Rutherford, in the county of Bergen and 5 State of New Jersey, have invented certain new and useful Improvements in Type-Writing Machines, of which the following is a specification.

My invention relates mainly to finely variable line-spacing mechanisms for type-writing machines, the primary object being to enable the operator to obtain mechanically any desired line-spacing interval, without the delay of repeated trial adjustments, 15 thus greatly facilitating his work and rendering the regulation of the line-spacing interval easy and rapid.

My line-spacing mechanism is completely variable within the extremes of its position, 20 i. e. it may be set to any position whatever, within its limits of position.

The desired adjustment is secured by merely operating the line-spacing lever in the usual manner to rotate the platen 25 through the line-spacing interval desired. The line-spacing lever, in addition to rotating the platen, also effects the adjustment of certain devices, which thereafter may limit the step-by-step advance of the platen. In other words, the line-space regulating mechanism is adjusted simultaneously 30 with the rotation of the platen by the usual lever through the required line-space interval.

35 The invention is particularly useful in writing on sheets having ruled lines, as well as for other purposes.

In carrying out the invention, I provide 40 the platen with a finely adjustable clutch mechanism driven by a line-spacing handle or lever. Permanent and shiftable stops control the throw of the clutch mechanism. A gage is adjustably mounted on the shiftable stop, to be set by the throw of the 45 line-spacing lever. Upon being adjusted, the gage is locked, and thereafter determines the position of said shiftable stop, and hence controls the throw of the line-space lever itself.

50 In the accompanying drawings, Figure 1 is a perspective view showing one embodiment of my invention applied to the Underwood type of front strike writing machine, the line-spacing mechanism being shown at the termination of its line-spacing

stroke. Fig. 2 is a side view showing the line-spacing mechanism in its position of rest, the gage-locking cam or nut, shown in dotted lines, being in released position. Fig. 3 is a detail side view, showing the 60 spacing lever-actuated regulating finger engaging the gage preparatory to setting the latter. Fig. 4 is a similar view showing the adjustment of the gage completed, the locking nut or cam, being shown (in dotted 65 lines) in locked position to retain the gage in set position. Fig. 5 is a similar view showing the positions occupied by the parts when the shiftable stop has been moved to its adjusted position, the gage being held 70 by the swinging latch. Fig. 6 is a cross-sectional detail view of the ratchet wheel and line-spacing clutch mechanism. Fig. 7 is a detail top plan view of the regulating mechanism. Fig. 8 is a detail cross-sectional 75 view showing one arrangement for locking the gage in set position. Fig. 9 is a detail perspective view of the clutching dog carrier. Fig. 10 is a detail perspective view of the locking nut or cam and its handle. 80 Fig. 11 is a collective view showing the adjustable stop and its arm, the gage and the bolt on which the locking nut is threaded, disassembled. Fig. 12 is a detail top perspective view of the clutch driving mechanism. Fig. 13 is a detail perspective view of the platen throw-controlling stops and the regulating mechanism therefor. Fig. 14 is a detail perspective view showing the 85 manner in which the clutch driving mechanism operates to mechanically adjust the line-space regulating mechanism.

The platen A is mounted on an axle 1 journaled in the ends of a platen frame 2, on which axle is fixed a ratchet 3 engaged 95 to a tooth 11 carried by a pawl 12 pivoted to a slide 13 driven by the usual line-spacing lever 15, against the tension of a return spring 14. By operating the line-spacing lever, the slide carrying the pawl and tooth, 100 is forced rearwardly to bring the tooth into mesh with the ratchet wheel 3 to rotate the platen for regular line-spacing, the slide and its connected parts being returned to inactive position by the spring 14.

A line-spacing clutch mechanism for effecting minute adjustments of the line-spacing intervals includes preferably, an annular clutch flange 4 conveniently mounted on the ratchet wheel 3 and engaged by the jaws 110

6 of a clutching dog 5 pivotally mounted on a carrier 7, the latter journaled on the platen axle adjacent the wheel 3, and the clutch dog being held yieldingly by a spring 31 against a stop 22. Pressure against the clutching dog 5 operates to vibrate the latter to cause its jaws 6 to bite the clutch flange 4, and then rotates the carrier and clutch flange to turn the platen, the carrier and clutching dog being spring-returned to normal inactive positions, when the pressure against the clutch dog is removed.

Preferably the driving tooth 11 is laterally shiftable to enable either the regular line-spacing mechanism or the clutch line-spacing mechanism to be operated at will by the line-spacing lever, and normally the tooth 11 is held by a spring 16 in position to engage the ratchet 3. When it is desired to operate the clutch mechanism, a switch 17 controlled by a lever 18 is swung to force the tooth laterally out of operative position relative to the ratchet and into position to effect the operation of the clutch mechanism when the line-space lever 15 is actuated. The tooth 11 carries a stud 10, which, when the tooth is shifted out of operative position with the ratchet wheel 3, engages beneath a shoulder 9 on a lever 8 pivoted to the carrier 7, the head of the lever engaging the outer end of the clutching dog 5 to actuate the latter.

To reduce the line-spacing intervals, the stop 22, against which the clutching dog 5 lies when at rest, is mounted so as to be adjusted toward a permanent stop 21 to reduce the distance the clutching dog travels at each line-space operation. The adjustable stop 22 is held yieldingly in one position by a spring 24; a lug 25 carried by the adjustable stop engaging the permanent stop 21 to limit the distance to which the adjustable stop can be urged by the spring. The shiftable stop 22 carries an arm 23, on which is adjustably mounted a gage 27. For illustration, the shiftable stop 22 and its arm 23 may be regarded as a rotatable elbow lever embracing a fixed stop 21, so that rotation of the gage-carrying arm away from the permanent stop will cause the remaining arm or stop 22 to advance toward the fixed stop 21 and thus decrease the distance afforded for the throw of the clutching dog between the stops. The gage is yieldingly held in one position by a spring 29.

A regulating finger 30 is provided on the dog carrier 7, which finger (when the lever 15 is being preliminarily employed for the purpose of setting the line-space regulator) sets the gage 27 relative to the stop 22 and against the tension of the spring 29. The gage when set is secured by a nut 32 on a threaded bolt 28 carried by the arm 23 and passing through a slot in the gage. A handle 33 is connected to the nut both to op-

erate the latter and also to swing the shiftable stop 22 (together with gage 27) against the tension of the spring 24, to move the stop 22 toward the permanent stop 21. This movement continues until the gage is caught and held by a latch 36.

To use the mechanism for regulating or determinating the proper line-spacing interval for a ruled sheet, for instance, so that the typewritten words will fall on the ruled lines, the sheet is inserted in the machine, and one of the ruled lines thereof is brought to the printing point. The operator then slowly operates the line-spacing lever 15, and this through tooth 11 moves dog 5 and the rest of the clutch mechanism from its position of rest, shown in Fig. 2, not only to rotate the platen and paper carried thereby, but also to bring the regulating finger 30 from its normal position of rest, shown in Fig. 2, to the position shown in Fig. 3, to depress the gage 27 more or less, as shown in Fig. 4, until the succeeding ruled line on the sheet appears at the printing point on the platen. Thereupon the gage is secured by turning the handle 33 and nut 32. Continued movement of this handle 33 in the same direction now rotates the shiftable stop 22 about the axis 1 toward the permanent stop 21, against the tension of spring 24, until the gage 27 is engaged by the latch 36 to hold the shiftable stop 22 in adjusted position; where it remains during the subsequent operation of the machine.

Subsequent operations of the line-spacing lever will throw the platen through intervals equal to the interval just measured by the line-spacing lever when adjusting the regulating mechanism in the manner described.

It will be seen that, at the gage-setting operation, the shiftable stop 22 advances toward the permanent stop 21, until the gage 27 is caught by its latch 36; and hence if the movement imparted to the gage by the finger 30 is small, the distance through which the gage must then be rotated in order to be caught by the latch will be correspondingly large, and the stop 22 will be carried a correspondingly great distance toward fixed stop 21. If, on the other hand, the lever 15 sets the gage 27 down a great distance, then the movement of the stop 22, subsequently effected by handle 33 will be correspondingly small.

To release the line-space regulating mechanism, the handle 33 releases nut 32 from the gage 27, and strikes a pin 39 on the latch 36 to turn it and release the gage 27, whereupon the spring 24 swings the stop 22 away from the permanent stop 21, and lug 25 strikes the permanent stop 21. Spring 29 elevates the gage.

The arm 23 is preferably provided with a

- grooved head 26 in which slides the gage 27, and the rotation of the lock nut 32 is arrested by a pin 34 carried by the handle 33 and engaging the head 26.
5. Preferably the latch 36 is pivotally supported and is provided with a counter-weight 37 tending to swing the free end of the latch to catch over the gage.
10. Variations may be resorted to within the scope of the invention, and portions of the improvements may be used without others.
- Having thus described my invention, I claim:
1. In a typewriting machine, the combination with a platen, and a line-spacing mechanism completely variable within extremes therefor, including a lever, of a line-space regulating mechanism including an element adjustable by said lever for identically determining successive line spaces, and means for locking said element in adjusted position.
15. 2. In a typewriting machine, the combination with a platen, and a line-spacing mechanism therefor, including a lever, of a regulating mechanism for identically determining successive line-spaces adapted to be adjusted by the line-spacing lever, a setting device, and a locking device for detaining the regulating mechanism in adjusted position, whereby to effect variations in line spacing intervals.
20. 3. In a typewriting machine, the combination with a platen and a line spacing mechanism therefor, including a lever, of a gage shiftable by said lever for identically determining successive line-spaces adjusted by the line-spacing lever to effect variations in the line-spacing intervals, and a locking device for detaining the shiftable gage in adjusted position.
25. 4. In a typewriting machine, the combination with a platen and a line-spacing mechanism therefor, including a lever, of a slotted gage shiftable by said lever for identically determining successive line-spaces adjusted by the line-spacing lever to effect variations in the line-spacing intervals, a stud passing through the slot, and a locking member on the stud for holding the gage in adjusted position.
30. 5. In a typewriting machine, the combination with a platen, and a line-spacing mechanism therefor, including a lever, of a spring-actuated regulating mechanism including an element adjustable by the line-spacing lever, to effect variations in the line-space intervals.
35. 6. In a typewriting machine, the combination with a platen, and a line-spacing mechanism therefor, including a lever, of a spring-actuated shiftable gage adjusted by the line-spacing lever, to effect variations in the line-space intervals, and a locking device for detaining the shiftable gage in adjusted position against the spring tension.
7. In a typewriting machine, the combination with a platen, and a line-spacing mechanism therefor, including a lever, of a spring-actuated slotted gage adjusted by the line-spacing lever to effect variations in the line-spacing intervals, a stud passing through the slot, and a locking member on the stud for holding the gage in adjusted position.
70. 8. In a typewriting machine, the combination with a platen, a line-spacing mechanism therefor, including a lever, and a shiftable stop controlling the line-spacing throw of the platen, of a regulating-mechanism connected to the stop and including a member movable relatively to the stop and settable at a point determined by the line-spacing lever for controlling the extent of shift of the shiftable stop to vary the line-spacing interval.
75. 9. In a typewriting machine, the combination with a platen, a line-spacing mechanism therefor, including a lever, and a shiftable stop controlling the line-spacing throw of the platen, of a regulating mechanism, including a shiftable gage connected to the stop and settable at a point determined by the line-spacing lever for determining the extent of shift of the stop to vary the line-spacing interval.
80. 10. In a typewriting machine, the combination with a platen, a line-spacing mechanism therefor, including a lever, and a shiftable stop controlling the line-spacing throw of the platen, of a regulating mechanism, including a shiftable gage connected to the stop and settable at a point determined by the line-spacing lever for determining the extent of shift of the stop to vary the line-spacing interval.
85. 11. In a typewriting machine, the combination with a platen, a line-spacing mechanism therefor, including a lever, and a shiftable stop controlling the line-spacing throw of the platen, of a regulating mechanism, including a shiftable gage connected to the stop and settable at a point determined by the line-spacing lever for determining the extent of shift of the stop to vary the line-spacing interval, a locking device for detaining the gage where adjusted, and a finger-piece to operate the locking device.
90. 12. In a typewriting machine, the combination with a platen, a line-spacing mechanism therefor, including a lever, and a shiftable stop controlling the line-spacing throw of the platen, of a regulating mechanism, including a shiftable gage connected to the stop and settable at a point determined by the line-spacing lever for determining the extent of shift of the stop to vary the line-spacing interval, a locking device for detaining the gage in adjusted position, a finger piece to operate the lock-
95. 100. 105. 110. 115. 120. 125. 130.

- ing device, and an arrester for limiting the swing of the finger piece.
13. In a typewriting machine, the combination with a platen, and a line-spacing mechanism therefor, including a lever, of a spring-actuated shiftable stop controlling the throw of the line-spacing mechanism and platen, and regulating mechanism settable at a point determined by the line-spacing lever for determining the extent of the shift of the shiftable stop to vary the line-spacing intervals.
14. In a typewriting machine, the combination with a platen, and a line-spacing mechanism therefor, including a lever, of a spring-actuated shiftable stop controlling the throw of the line-spacing mechanism and platen, an arrester carried by the stop and engaging an abutment to limit the spring-actuated throw of the stop in one direction, and regulating mechanism settable at a point determined by the line-spacing lever for determining the extent of shift of the shiftable stop to vary the line-spacing intervals.
15. In a typewriting machine, the combination with a platen, and a line-spacing mechanism therefor, including a lever, of a spring-actuated shiftable stop controlling the throw of the line-spacing mechanism and platen, and an adjustable gage connected to the stop and settable at a point determined by the line-spacing lever, for determining the extent of shift of the stop to vary the line-spacing intervals.
16. In a typewriting machine, the combination with a platen, and a line-spacing mechanism therefor, including a lever, of a spring-actuated shiftable stop controlling the throw of the line-spacing mechanism and platen, regulating mechanism settable at a point determined by the line-spacing lever for determining the extent of shift of the shiftable stop to vary the line-spacing intervals, and a locking device for detaining the stop in adjusted position.
17. In a typewriting machine, the combination with a platen, and a line-spacing mechanism therefor, including a lever, of a spring-actuated shiftable stop controlling the throw of the line-spacing mechanism and platen, regulating mechanism settable at a point determined by the line-spacing lever for determining the extent of shift of the shiftable stop to vary the line-spacing intervals, a locking device for detaining the gage in adjusted position, and a retaining member with which the gage coöperates for holding the stop in its shifted position.
18. In a typewriting machine, the combination with a platen, and a line-space mechanism therefor, including a lever, of a shiftable stop controlling the throw of the line-space mechanism and platen, a stop-shifting device, and a gage set at a point determined by the line-spacing lever for determining the extent to which the stop shall be shifted, to effect variations in the line-spacing interval.
19. In a typewriting machine, the combination with a platen, and a line-space mechanism therefor, including a lever, of a shiftable stop controlling the throw of the line-space mechanism and platen, a stop-shifting device, a gage set at a point determined by the line-spacing lever for determining the extent to which the stop shall be shifted, to effect variations in the line-spacing interval, and a retaining device for detaining the stop in shifted position.
20. In a typewriting machine, the combination with a platen, and a line-space mechanism therefor, including a lever, of a shiftable stop controlling the throw of the line-space mechanism and platen, a stop-shifting device, a gage set at a point determined by the line-spacing lever for determining the extent to which the stop shall be shifted, to effect variations in the line-spacing interval, and a retaining device with which the gage is engaged in shifting the stop, for detaining the stop in shifted position.
21. In a typewriting machine, the combination with a platen, and a line-spacing mechanism therefor, including a lever, of a spring-actuated shiftable stop controlling the throw of the line-spacing mechanism and platen, regulating mechanism including a gage settable at a point determined by the line-spacing lever for determining the extent of shift of the shiftable stop to vary the line-spacing intervals, a locking device for detaining the gage in adjusted position, and a retaining member, to coöperate with the gage and hold the stop where adjusted.
22. In a typewriting machine, the combination with a platen, and a line-spacing mechanism therefor, including a lever, of a spring-actuated shiftable stop controlling the throw of the line-spacing mechanism and platen, regulating mechanism including a gage set at a point determined by the line-spacing lever for determining the extent to which the stop shall be shifted, whereby to vary the line-space intervals, a stop-shifting device for detaining the gage in adjusted position and for shifting the stop, and a latch coöperating with the gage for holding the stop in shifted position.
23. In a typewriting machine, the combination with a platen, and a line-spacing mechanism therefor, including a lever, of a spring-actuated shiftable stop controlling the throw of the line-spacing mechanism and platen, regulating mechanism including a gage set at a point determined by the line-spacing lever for determining the extent to which the stop shall be shifted, whereby to

vary the line-space interval, and a stop-shifting device for detaining the gage in adjusted position and for shifting the stop.

24. In a typewriting machine, the combination with a platen, and a line-spacing mechanism therefor, including a lever, of a spring-actuated shiftable stop controlling the throw of the line-spacing mechanism and platen, regulating mechanism including a gage set at a point determined by the line-spacing lever for determining the extent to which the stop shall be shifted, whereby to vary the line-space interval, a stop-shifting device for locking the gage in adjusted position and for shifting the stop, and a retaining device automatically operating to retain the stop in its shifted position.

25. In a typewriting machine, the combination with a platen, line spacing mechanism therefor, said line spacing mechanism including a lever, an adjustable stop controlling the line spacing mechanism and the platen, of a regulating mechanism for said adjustable stop whereby variations of the line spacing intervals may be effected, said line spacing mechanism being provided with a finger adapted to engage the regulating mechanism to aid in determining the point of adjustment of such mechanism.

30. 26. In a typewriting machine, the combination with a platen, line-spacing mechanism therefor, including a lever, and an adjustable stop controlling the throw of the line-space mechanism and platen, of an adjusting mechanism for the stop whereby to effect variations of the line-space intervals, a member operated by the spacing lever for adjusting the regulating mechanism, and means for holding said mechanism in adjusted position.

45. 27. In a typewriting machine, the combination with a platen, line-spacing mechanism therefor, including a lever, and an adjustable stop controlling the throw of the line-space mechanism and platen, of a regulating mechanism for the stop whereby to effect variations of the line-space intervals, a member operated by the spacing lever for adjusting the regulating mechanism, and a locking device for detaining the regulating mechanism in adjusted position.

55. 28. In a typewriting machine, the combination with a platen, and a line-spacing mechanism therefor including a lever, of a shiftable stop controlling the throw of the line-space mechanism and platen, a gage adjustably connected with the stop, and a member operated by the spacing lever for adjusting the gage, means for holding the gage in adjustable position whereby to effect variations in the line-spacing interval.

65. 29. In a typewriting machine, the combination with a platen, and a line-spacing mechanism therefor, including a lever, of a shiftable stop controlling the throw of the

line-space mechanism and platen, a gage adjustably connected with the stop, a member operated by the spacing lever for adjusting the gage relatively to the stop, a lock for releasably retaining the gage in its adjusted position and for rocking the stop and gage bodily to effect variations in the line-space interval, and a shiftable latch for preventing the stop from returning to the position from which it was rocked.

75. 30. In a typewriting machine, the combination with a platen, and a line-spacing mechanism therefor including a lever, of a shiftable stop controlling the throw of the line-space mechanism and platen, a gage adjustably connected with the stop, a member operated by the spacing lever for adjusting the gage relatively to the stop, a lock for releasably retaining the gage in its adjusted position and for rocking the stop and gage bodily to effect variations in the line-space interval, and a shiftable latch automatically projected into the path of return movement of the gage to prevent the stop from returning to the position from which it was rocked.

80. 31. In a typewriting machine, the combination with a platen, and a line-spacing mechanism therefor including a lever, of a shiftable stop controlling the throw of the line-space mechanism and platen, a gage adjustably connected with the stop and set at a point determined by the spacing lever relatively to the stop, a locking device for retaining the gage in adjusted position, said locking device having a handle for rocking the stop and gage bodily to shift the stop in effecting variations in the line-space interval, and a latch with which the gage is brought into engagement in shifting the stop, to maintain the stop in shifted position.

95. 32. In a typewriting machine, the combination with a platen, and a line-spacing mechanism therefor, including a lever, of a shiftable stop controlling the throw of the line-space mechanism and platen, a gage adjustably connected with the stop and set at a point determined by the spacing lever relatively to the stop, a locking device for retaining the gage in adjusted position, said locking device having a handle for rocking the stop and gage bodily to shift the stop in effecting variations in the line-space interval, and a latch with which the gage is brought into engagement in shifting the stop, to maintain the stop in shifted position; the latch being engaged by the handle when releasing the gage, to effect the disengagement of the latch and gage.

100. 110. 120. 125. 33. In a typewriting machine, the combination with a platen, and a line-spacing mechanism therefor, including a lever, of a shiftable stop controlling the throw of the line-space mechanism and platen, a gage ad-

- justably connected with the stop, a member 5 operated by the spacing lever for adjusting the gage relatively to the stop, a lock for releasably retaining the gage in its set position and for rocking the stop and gage bodily to effect variations in the line-space interval, a shiftable retaining device automatically projected into the path of the gage to retain the stop in shifted position, and 10 a projection on the retaining device engaged by the locking handle when moved to release position to effect the disengagement of the latch and gage.
34. In a typewriting machine, the combination with a platen, a line-spacing mechanism therefor, including a lever, and a shiftable stop controlling the line-spacing throw of the platen, of an adjustable gage controlled by the line-spacing lever for effecting 15 the adjustment of the shiftable stop to vary the line-spacing interval, a spacing device, a latch, and means whereby said latch is automatically projected into operative engagement with the gage when the stop has been shifted the predetermined distance, for detaining the stop in adjusted position.
35. In a typewriting machine, the combination with a platen, of a line spacing mechanism completely variable within the extremes, said mechanism including a clutch and also including a lever, and an adjustable regulating mechanism therefor, the adjustment of which mechanism is determined by 20 the lever.
36. In a typewriting machine, the combination with a platen, of a line-spacing clutch mechanism completely adjustable within extremes, including a lever, an adjustable regulating mechanism therefor, the adjustment of which is determined by the lever, and locking means for detaining the regulating mechanism in adjusted position.
37. In a typewriting machine, the combination with a platen, of a line-spacing clutch mechanism, minutely adjustable within its 25 limits of movement, including a lever, a regulating mechanism therefor including an adjustable gage the adjustment of which is determined by the lever, and a locking means for detaining the regulating mechanism in adjusted position.
38. In a typewriting machine, the combination with a platen, of a line-spacing clutch mechanism including a lever, a regulating mechanism therefor including a gage, means connected with the lever whereby to 30 adjust the gage, a latch, and means whereby said latch is made to coöperate with the gage in order to maintain the regulating mechanism in adjusted position.
39. In a typewriting machine, the combination with a platen, of a finely variable line-spacing clutch mechanism including a lever, an adjusting mechanism therefor including a gage, means connected with the lever 35

lever whereby to adjust the gage, a locking lever for detaining the gage where adjusted, and locking means coöperating with the gage to maintain the adjusting mechanism in adjusted position.

70

40. In a typewriting machine, the combination with a platen and a line-spacing mechanism therefor including a lever, of a line-space regulating mechanism including a shiftable stop controlling the throw of the line-space mechanism and platen, a gage connected with the stop, means for mechanically determining the point at which it is to be set simultaneously with the lever-actuated rotation of the platen, and retaining means for holding the stop in its shifted position determined by the mechanical adjustment of the gage.

80

41. In a typewriting machine, the combination with a platen and a line-spacing mechanism therefor, including a lever, of a line-space regulating mechanism including a shiftable stop controlling the throw of the line-space mechanism and platen, a gage connected with the stop, means for mechanically determining the point at which it is to be set simultaneously with the lever-actuated rotation of the platen, a lock for holding the gage in set position, and a retaining means with which the gage is engaged when the stop is shifted to maintain the stop in shifted position.

90

42. In a typewriting machine, the combination with a platen, of both regular line-spacing mechanism and finely-variable line-spacing mechanism therefor, a stop, a gage on said stop for said finely-variable line-spacing mechanism, a lever for adjusting said stop, a second lever for setting said gage, a lock, and a shifting lever whereby either spacing mechanism may be thrown into operative relation with the platen.

105

43. In a typewriting machine, the combination with a platen, of a finely variable line-spacing clutch mechanism, including a lever, an adjusting mechanism therefor including a gage, adjusted by the lever, a nut to hold the gage in adjusted position, and a handle for effecting the engagement and disengagement of the nut and gage.

110

44. In a typewriting machine, the combination with a platen, of a finely variable line-spacing mechanism therefor, including a clutch element connected with the platen, a lever and a co-acting clutch member operated by the lever for rotating the clutch element and platen, a regulating mechanism including an adjustable stop controlling the throw of the platen, and a finger connected to one of the clutch members and swinging therewith for positioning said adjustable stop.

120

45. In a typewriting machine, the combination with a platen, and a line-spacing clutch mechanism connected therewith, in-

130

cluding a lever, of a shiftable stop controlling the throw of the clutch mechanism and platen, a stop-adjusting mechanism shiftable with the stop and movable to adjusted position by the line-spacing lever, and a lock for detaining the stop in adjusted position.

46. In a typewriting machine, the combination with a platen, and line-spacing mechanism therefor, including a lever, of an adjusting mechanism including an adjustable stop controlling the throw of the line-space mechanism and platen, and tending to move in one direction, an arrester for determining the travel of the stop in such direction, and means for shifting the stop.

47. In a typewriting machine, the combination with a platen, and line-spacing mechanism therefor, including a lever, of a regulating mechanism including an adjustable stop controlling the throw of the line-space mechanism and platen, and tending to move in one direction, an arrester for determining the travel of the stop in such direction, means adjusted by the line-space lever for shifting the stop to effect variations in the line-space interval and means for holding the stop in adjusted position.

48. In a typewriting machine, the combination with a platen, and a line-space mechanism therefor, including a lever, of a shiftable stop controlling the throw of the line-space mechanism and platen, an adjustable member connected with the stop and set at a point determined by the line-spacing lever for regulating the extent to which the stop is shifted, and combined means for locking the adjustable member in set position and for shifting the stop to effect variations in the line-spacing interval.

49. In a typewriting machine, the combination with a platen equipped with a ratchet and also with a line spacing mechanism completely variable within extremes, said line spacing mechanism including a lever, of an adjustable gage coöperating with said lever, the position of said adjustable gage being determinable in accordance with some position of the lever, means to set said adjustable gage in said determined position and a lock.

50. In a typewriting machine, the combination with a platen, of a line-spacing mechanism therefor including a lever, a regulating mechanism including a stop shiftable against the tension of a spring for controlling the throw of the line-spacing mechanism and platen, an adjusting mechanism connected with the stop, and a finger operated by the lever to control the adjusting mechanism to effect variations in the line-spacing interval.

51. In a typewriting machine, the combination with a platen and a line-space mechanism including a lever, of an adjustment for varying the line-spacing intervals in-

cluding a shiftable stop controlling the throw of the line-spacing mechanism and platen, an adjustable gage connected with the stop, a finger operated by the lever for determining the setting point of the gage relatively to the stop, a lock for releasably maintaining the gage in set position and to effect the shifting of the stop, and a detaining device for holding the stop in the position to which it has been shifted, to vary the line-spacing interval.

52. In a typewriting machine, the combination with a platen, and a line-space mechanism including a lever, of regulating mechanism for varying the line-spacing intervals, including a shiftable stop controlling the throw of the line-spacing mechanism and platen, an adjustable gage connected with the stop, an actuator operated by the lever for determining the setting point of the gage relative to the stop, a lock for releasably maintaining the gage in set position and to effect the shifting of the stop, and a detaining device engaging the adjusted gage for holding the stop in the position to which it has been shifted, to vary the line-spacing interval.

53. In a typewriting machine, the combination with a platen, and a line-spacing mechanism including a lever, of an adjustment for varying the line-spacing intervals, including a shiftable stop having an arm, a grooved head on the arm, a gage slidably received in the head, an actuator operated by the lever for determining the setting point of the gage relative to the head and stop, a lock for maintaining the gage in set position, and a latch with which the gage is engaged in shifting the stop to maintain it in the position to which it has been shifted, to vary the line-spacing interval.

54. In a typewriting machine, the combination with a platen, and a line-space mechanism including a lever, of an adjustment for varying the line-spacing intervals, including a shiftable stop having an arm, a gage adjustably mounted on the arm, an actuator operated by the lever, for determining the setting point of the gage relative to the arm and stop, a lock for maintaining the gage in set position, and a latch with which the gage is engaged in shifting the stop to maintain it in the position to which it has been shifted, to vary the line-spacing interval.

55. In a typewriting machine, the combination with a platen and a line-spacing mechanism therefor, including a lever, of a shiftable stop controlling the line-spacing throw of the platen, a gage carried by the stop and adjustable relatively thereto to determine the variation in the throw of the platen, and a retaining device for engagement with the gage when the latter is shifted together with the stop, to maintain the stop in shifted position.

56. In a typewriting machine, the combination with a platen, of a line-spacing mechanism including a clutch element connected with the platen, a swinging carrier 5 on which is pivotally mounted a clutching dog for engaging and operating the clutch element and platen, a lever having a shoulder for vibrating the clutching dog to cause it to bite the clutch element, an actuator having a pin to engage the shoulder to operate the transmission lever and effect the rotation of the platen and clutch, and a lever to drive the actuator.
57. In a typewriting machine, the combination with a platen, of a regular line-spacing mechanism, a minutely variable line-spacing clutch mechanism, both connected with the platen, a lever, a shiftable pawl actuated thereby for actuating either the 10 regular line-spacing or the minutely variable line-spacing clutch mechanism, a switch for controlling the position of the pawl relatively to the respective line-spacing mechanisms, and an adjustment for the minutely 15 variable line-spacing clutch mechanism including a shiftable stop controlling the line-spacing throw of the clutch mechanism and platen, and an adjustable gage connected to the stop and positioned by the lever for 20 effecting variations in the line-spacing interval.
58. In a typewriting machine, the combination with a platen, and line-spacing mechanism therefor, including a lever, of a shift- 25 able stop controlling the throw of the line-space mechanism and platen, a gage carried by the stop and overlapping a latch, the gage being positioned at a point determined by the lever in rotating the platen, to overlap 30 the latch to a greater or less extent, and a locking device for holding the gage in set position, the stop being shiftable until the gage is operatively engaged by the latch to hold the stop in shifted position.
59. In a typewriting machine, the combination with a platen, and line-spacing mechanism therefor, including a lever, of a shift- 35 able stop controlling the throw of the line-space mechanism and platen, a gage carried by the stop and overlapping a latch, the gage being positioned at a point determined by the lever in rotating the platen, to overlap 40 the latch to a greater or less extent, and a locking device for holding the gage in set position, the stop being shiftable until the gage is operatively engaged by the latch to hold the stop in shifted position.
60. In a typewriter, the combination with a platen, of a line-spacing mechanism comprising a shiftable part adjustable for determining the throw of the line-space, a swinging latch, and a counter-weight being 45 said latch into the path of the said shiftable part to hold it in its shifted position, 50 substantially as set forth.

61. In a typewriting machine, the combination with a platen, of a line-spacing device therefor, a pivoted member forming a part of and movable with said device, a finely adjustable line-space regulating device 70 including an element adjustable by said pivoted member, a setting device and a latch for holding said adjustable element, so that successive line spaces may be identically determined by said element.

62. In a typewriting machine, the combination with a platen, of a line-spacing device therefor, a pivoted member forming a part of and moving with said device, a finely-adjustable line-space regulating element adjustable by said pivoted member, a locking device for said element, and a latch for said adjustable element, so that successive line-spaces may be identically determined thereby.

63. In a typewriting machine, the combination with a rotatable platen, of a line-space lever therefor, a lever rotatable on the axle of said platen, a dog pivoted on said lever arranged to bite a flange on a wheel fast on said axle, a fixed stop, an adjustable swinging stop comprising arms arranged to be limited by said fixed stop, and an arm on said lever arranged to be arrested by said adjustable stop.

64. In a typewriting machine, the combination with a platen and a line-spacing mechanism therefor, including a lever, of an arm pivoted on the platen axle, a gage adjustable on said arm by the line-spacing lever to vary the operative position of said arm and thereby effect variations in the line-spacing intervals, means for holding the gage in adjusted position and a latch for holding said arm.

65. In a typewriting machine, the combination with a platen, of a completely variable line-spacing mechanism therefor, including a line-spacing lever, and an adjusting device movable by the line-spacing lever to different positions of adjustment, a setting device for effecting fine variations in the line-spacing intervals for identically determining successive line-spaces and means to hold said adjusting device after adjustment.

66. In a typewriting machine, the combination with a platen, of a completely variable line-spacing mechanism therefor including a line-spacing lever, an adjusting device movable by the line-spacing lever to different positions of adjustment, a setting device for effecting fine variations in the line-spacing intervals for identically determining successive line-spaces, and locking mechanism for detaining said adjusting device in set position.

67. In a typewriting machine, the combination with a platen, of a completely variable line-spacing clutch mechanism connect-

ed with the platen, and a regulating mechanism controlling the throw of the line-spacing mechanism and platen, said regulating mechanism including an adjustable stop
5 settable at a point determined by a line-spacing mechanism for regulating the posi-

tion of said regulating mechanism to effect variations in the line-space interval.
